US00D877338S

(12) **United States Design Patent** (10) **Patent No.:** **US D877,338 S**
(45) **Date of Patent:** **** Mar. 3, 2020**

(54) **XRF ANALYZER**

(71) Applicant: **Moxtek, Inc.**, Orem, UT (US)

(72) Inventors: **Vincent Floyd Jones**, Cedar Hills, UT (US); **Daniel N. Paas**, Spanish Fork, UT (US)

(73) Assignee: **Moxtek, Inc.**, Orem, UT (US)

(**) Term: **15 Years**

(21) Appl. No.: **29/673,532**

(22) Filed: **Dec. 14, 2018**

Related U.S. Application Data

(63) Continuation of application No. 15/936,082, filed on Mar. 26, 2018, now Pat. No. 10,219,363, which is a continuation of application No. 15/633,525, filed on Jun. 26, 2017, now Pat. No. 9,961,753, which is a continuation of application No. 14/615,134, filed on Feb. 5, 2015, now Pat. No. 9,775,574.

(57) **CLAIM**

The ornamental design for a XRF analyzer, as shown and described.

DESCRIPTION

FIG. 1 is a perspective view of the XRF analyzer in accordance with our invention;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and

FIG. 7 is a bottom plan view thereof;

FIG. 8 is a perspective view thereof without a battery;

FIG. 9 is a right side elevation view thereof without the battery;

FIG. 10 is a left side elevation view thereof without the battery;

FIG. 11 is a front elevation view thereof without the battery;

FIG. 12 is a rear elevation view thereof without the battery;

FIG. 13 is a top plan view thereof without the battery; and,

FIG. 14 is a bottom plan view thereof without the battery.

1 Claim, 14 Drawing Sheets
